To all whom it may concern:

Be it known that I, Sabina De Pasquale, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design;

Fig. 2 is a rear view of Fig. 1;

trating the coat member of the ensemble in closed position;

Fig. 4 is a front view of the dress member of the ensemble shown in Fig. 1, and

The characteristic feature of my design resides in the combination on the ensemble disclosed of the specific redingote member having full length revers which are shaped as shown.

I claim:
